CLAIM

(21) Appl. No.: **29/635,387**

The ornamental design for a particle sorting system, as
shown and described.

(22) Filed: **Jan. 30, 2018**

DESCRIPTION

(51) LOC (12) Cl. 24-01

FIG. 1 is a front perspective view of a particle sorting
system;

(52) U.S. Cl.

FIG. 2 is a front perspective view of the particle sorting
system, with the doors open;

USPC **D24/232**

FIG. 3 is a front view of the particle sorting system, with the
doors removed;

(58) **Field of Classification Search**

FIG. 4 is a back view of the particle sorting system;

USPC D24/107, 185, 186, 216, 231-234;

FIG. 5 is a first side view of the particle sorting system, with the
doors removed;

D10/81

FIG. 6 is a second side view of the particle sorting system,
with the doors removed;

CPC G01N 15/1436; G01N 21/05; G01N
21/6428; G01N 2015/1006; G01N

FIG. 7 is a top view of the particle sorting system, with the
doors removed;

2015/149; G01N 2015/1452; G01N

FIG. 8 is a bottom view of the particle sorting system, with the
doors removed;

2021/6439; B01L 2200/0652

FIG. 9 is a front view of the particle sorting system;

See application file for complete search history.

FIG. 10 is a first side view of the particle sorting system;

(56) **References Cited**

FIG. 11 is a second side view of the particle sorting system;

U.S. PATENT DOCUMENTS

FIG. 12 is a top view of the particle sorting system; and,

5,030,002 A * 7/1991 North, Jr. G01N 15/1404
209/3.1

FIG. 13 is a bottom view of the particle sorting system.
